INVENTOR

Charles A. Howard,
By W. W. Leggett,

ATTORNEY

UNITED STATES PATENT OFFICE.

CHARLES A. HOWARD, OF PONTIAC, MICHIGAN.

BOLSTER-SPRING.

SPECIFICATION forming part of Letters Patent No. 252,036, dated January 10, 1882.

Application filed November 8, 1881. (No model.)

To all whom it may concern:

Be it known that I, CHARLES A. HOWARD, of Pontiac, county of Oakland, State of Michigan, have invented a new and useful Improvement in Spring Attachments for Bolsters; and I declare the following to be a full, clear, and exact description of the same, such as will enable others skilled in the art to which it pertains to make and use it, reference being had to the accompanying drawings, which form a part of this specification.

My invention consists of the combination of devices and appliances hereinafter specified and described, and more particularly pointed out in the claim.

It is the object of my invention to produce a removable spring-frame having semi-elliptical springs so constructed and arranged as to make a convenient, elastic, and durable set of springs for use on a lumber-wagon, sand or dirt wagon, or any other similar wagon, and so made that when a heavy load is being carried all the springs are brought into use; but when the load is taken off and the wagon returning for another a part of the spring-power may be dispensed with, if desired. I accomplish these results by employing the mechanism illustrated in the accompanying drawings, in which—

Figure 1 is a view of the removable spring-frame, with springs attached, as it appears when adjusted to the bolster of a lumber-wagon. Fig. 2 shows the same when detached from the bolster. Fig. 3 is a view of the spring-frame when the cross-spring is not in use, as is the case when the load is off the wagon. Fig. 4 is a separate view of one of the side pieces of the frame, showing another method of attachment of the spring thereto. Fig. 5 shows a variation where two cross-springs are employed instead of one, as in Fig. 1.

A is the bolster, and B B the wagon-stakes, of a common lumber-wagon.

C C represent a removable longitudinal spring-frame composed of two side pieces, D D, adapted to fit upon the bolster, said pieces having metallic plates screwed to their upper sides to receive the wear of the cross-spring D'.

E E are semi-elliptical springs, placed over the side pieces, with their length in the direction of the length of said pieces, and their concave side toward the plated surface of the

side pieces, each of their ends resting in a recess formed by the upturned flange on the end of the metallic plate aforesaid, and a strap passing over the end of the said plate directly in front of the flange, and secured in the usual manner.

F is a cross-bar uniting the two springs E E, and having pivoted to its central point a cross-spring, D', made in the same form as the other springs, but of such length as to enable it to reach from one side of the frame to the other, and its ends to rest upon the metallic plate, above described, when it is desired to employ it as shown in Fig. 1.

When the device is used upon a common lumber-wagon the removable frame is placed in position upon the bolster, and the body of the wagon will rest upon the cross-bar F.

It will be readily seen that as the spring D is directly over the bolster, two shorter springs of similar shape may be employed for the same purpose, each of these springs being pivoted to the cross-bar F in the same way as the spring D' aforesaid, thereby allowing them to be turned aside when not in use. In this latter case the appearance of the device will be as shown in Fig. 5.

If desired, the springs E E may have their ends turned down over the ends of the side pieces, and have slots made in them, through which a bolt passes, thus enabling the spring to flex, but not permitting it to leave its place on the side piece. This method of attachment is perhaps preferable to the one shown in Fig. 1, being somewhat cheaper.

A latchet device of any suitable construction may be employed to hold the cross-spring D' in position at right angles to the cross-bar when not in use.

It will be apparent from the above description that a removable frame, with a set of springs arranged in the manner shown, and capable of ready attachment to a wagon-bolster, is an article of great use and value. This device may be made separate, so as to be readily placed upon the bolster of any ordinary wagon; or, if desired, the side pieces may be framed into the bolster and made a permanent fixture. I prefer, however, to make it removable as a ready attachment. So, also, the top of the side pieces may or may not be shod with

metal, or may be shod only where the ends of the springs wear upon them.

It is apparent that a cross-piece similar to D may be interposed between the two side pieces, and be provided with a spring in like manner. For ordinary light work the cross-spring may be omitted, and the removable frame consist only of the side pieces and their springs united by the top bar parallel with the bolster.

Having thus described my invention, what I claim as new, and desire to secure by Letters Patent, is—

The removable spring attachment for a wag-

on, consisting of notched side pieces, a longitudinal semi-elliptic spring upon each side piece, a cross-bar parallel to the bolster uniting the tops of the springs, and a semi-elliptic cross-spring beneath the bar, and adapted to be thrown into or out of gear by rotating it about its point of attachment to the said bar, substantially as and for the purposes described.

In testimony whereof I sign this specification in the presence of two witnesses.

CHARLES A. HOWARD.
